(57) **CLAIM**

We claim the ornamental design for step ladder, as shown and described.

DESCRIPTION

FIG. 1 is a front perspective view of a step ladder.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof; and,

FIG. 8 is a rear perspective view thereof.

The dashed broken lines in the drawings depict portions of the step ladder that form no part of the claimed design.
